CLAIM

The ornamental design for a clip-on electromagnetic shielding gasket, as shown and described.

DESCRIPTION

FIG. 1 is a perspective view taken from the front and right end of a clip-on electromagnetic shielding gasket showing my new design;

FIG. 2 is a left end elevational view thereof;

FIG. 3 is a front elevational view thereof;

FIG. 4 is a top plan view thereof;

FIG. 5 is a rear elevational view thereof; and,

FIG. 6 is a bottom plan view thereof.

It is to be understood that the center of the gasket is shown broken away in FIGS. 1 and 3 through 6 to indicate indeterminate length.
